UNITED STATES PATENT OFFICE

HARRY LEBERMAN, OF NEW YORK, N. Y., ASSIGNOR TO GROOVE LOCK CO. INC., OF NEW YORK, N. Y., A CORPORATION OF NEW YORK

FASTENING MEANS FOR BAG FRAMES

Application filed December 27, 1930. Serial No. 505,048.

The present invention relates to improved fastening means for bag frames and is illustrated herein in association with handbag frames, for which the invention is more particularly adapted, although the use of the invention is not confined to that particular type of bag frames.

An object of the invention is the provision, in a manner as hereinafter set forth, of a fastening device for bag frames of the kind in which a pair of frame members are pivotally connected together to provide for the opening and closing of the bag, the invention being more particularly related to a simplified inexpensive construction for securing the frame members together in closed relation and capable of being readily released to allow swinging of the members away from each other in the act of opening the bag.

More particularly, my improved fastening device involves the provision of a retaining piece on one frame member, and of a catch slide on the other member movable into and out of a position in which it will interlock with the retaining piece; and according to a novel feature of the invention the catch slide is mounted directly on its frame member so as to have sliding contact therewith, its construction including relatively small central bearing or wear plates in sliding engagement with the outer and inner faces, respectively, of the frame member and web or shank-like members connecting the bearing parts and working in longitudinal slots provided in the frame member.

A further object of the invention is to provide an improved catch slide which is mounted for sliding movement directly on the horizontal top of the frame member and with a tight sliding fit thereon so that there will be no rattling or canting of the slide upon the frame.

With the foregoing and other objects in view, the invention consists of the construction, combination and relative arrangement of parts as will be hereinafter more fully described and illustrated in the accompanying drawing, wherein two simple and prac-

tical embodiments are shown by way of example.

In the drawing, wherein like reference characters denote corresponding parts throughout the several views:

Fig. 1 represents an elevational view of a handbag frame embodying my improved fastening device, the catch slide being disengaged from its retainer piece and the frame members being shown in partially open condition;

Fig. 2 is a plan and section on a larger scale, taken on the line 2-2 of Fig. 1;

Fig. 3 represents a vertical section, taken on the line 3-3 of Fig. 2;

Fig. 4 represents a cross section through the frame members in closed condition and showing the slide interlocking with the retainer piece; and

Fig. 5 represents a fragmentary top plan view of the cooperating frame members and showing a modification in the construction of the slide and retainer piece.

The invention is illustrated as embodied in a handbag frame comprising frame members 10 and 11, the terminals of which are pivoted together at 12 to enable the members to be closed against each other and to be opened in the act of closing and opening the handbag. In the present instance the frame member 11 is made all around with a flange 13 against the free edge of which the frame member 10 contacts when the bag is in closed condition.

Projecting inwardly from the inner face 14 of the frame member 10 is an elongated retainer piece 15 having an upstanding strip or flange 16 which, being opposite the said inner face 14, defines therewith a space or pocket 17.

A catch slide, denoted generally by the reference character 18, is mounted directly to the horizontal portion 19 of the flange 13 so as to be moved longitudinally of the frame member. In the present exemplification this catch slide comprises a rectangular body 20 with which is united a block-like part 21 having ornamental value and which may, if desired, constitute a setting for gems or stones. A rectangular bearing or wear plate 100

22, much smaller in size than the body 20, is united with the body at the underneath side thereof and in a central position. This wear plate slides in contact with the top surface of the horizontal flange portion 19, and in the form herein shown it is made with two longitudinally-extending, downwardly-projecting shank or web portions 23 which have sliding fit in longitudinally extending slots 24 provided in the horizontal portion 19. Below the horizontal portion 19, these shank or web portions are united with a lower bearing or wear plate 25 which slides in contact with the under surface of the horizontal portion 19. The body 20 with the block member 21 and the connected upper and lower bearing or wear plates 22 and 25, which slide in contact with the upper and underneath surfaces of the horizontal top 19, constitute a rigid structure which has tight sliding fit on the horizontal portion 19 for movement longitudinally of the frame. Owing to the fact that the upper and lower wear plates have flat sliding contact with the opposite sides of the horizontal portion 19 and are rigidly connected by the shank or web portions 23, a sturdy and reliable construction is provided and one which prevents any rattling or canting of the catch piece upon the frame. One of the shank or web portions 23, herein shown to be the one which comes closest to the frame member 10 when the bag is closed, extends downwardly beyond the underneath surface of the bearing plate 25 so as to provide a longitudinally extending catch lug or lip 26 which is adapted to enter the space or pocket 17 and interlock with the strip or flange 16 of the retainer piece 15. The slots 24 are, of course, long enough to permit the catch slide to be moved to and from a position in which the lug or lip 26 will interlock with the strip 16 of the retainer piece; and it will of course be understood in this connection that the walls 27 and 28 which define the opposite ends of the slots constitute stop means for the shank or web portions 23 whereby to limit the extent of movement of the catch slide in either direction. The retainer piece and slots are so related and proportioned that when the catch slide is moved to the left to the extent permitted by the walls 27, the lug 26 will be in interlocking engagement with the strip 16, whereas when the catch piece has been moved 55 against the opposite walls 28 the said lug 26 will be in a position clear of the strip 16. Means are provided for resiliently holding the catch slide in either of its terminal positions; the means to this end comprising, in the present embodiment, the provision of detent portions 29 and 30 which are struck from the lower bearing plate 25. These detents have an upwardly acting tension against the underside of the horizontal portion 19; and when the catch piece is moved to the left as

far as it will go the detent 29 slips into an indenture 31 provided for the purpose in the horizontal top portion 19. When the catch piece is moved to the right as far as it will go the detent 30 slips into a corresponding indenture 32. In this way, provision may be made for automatically retaining the catch piece at either of its terminals and against any accidental or unwarranted movement.

In Fig. 5 I show a modified form of construction, in which the retainer piece comprises an elongated block 33 having adjacent the inner face of the frame member 10 a channel 34 open at 35 at one end of the block. In this modified form of construction, the lug or lip 26 of the first described construction, is made in the form of a horizontal prong 36 adapted to enter the channel 34 through the open end 35 of the block. The prong 36 is united at one end to a portion 38 laterally offset from the inner shank or web 23 at a suitable point below the bearing plate 25.

From the foregoing description, taken in connection with the accompanying drawing, the construction, manner of operation, and the several advantages of my improved fastening device will be clearly and fully understood. It will be observed that the parts are few in number, and simple in design so as to be economical in manufacture. The upper ornamental portion 21 of the catch slide serves as a convenient finger grip by which readily to move the slide along the frame member either into interlocking engagement with the retainer piece when the frame members are in closed relation, or out of interlocking engagement with said piece when the frame members are to be moved from each other in the act of opening the handbag. While in the present instance, I have shown two shanks or webs operating in slots and connecting upper and lower bearing plates, it will be recognized that in practice, if it is desired, a single shank or web may be provided between the bearing plates, in which case only a single slot will be necessary in the top portion 19. It will also be recognized that, instead of employing the upper wear plate 22, the body 20 may carry the shank or web directly and itself have sliding engagement with the horizontal portion 19.

While I have shown and described the preferred constructions and arrangements of the several parts of my fastening device, it is, of course, to be understood that these constructions are susceptible of considerable modification and I, therefore, reserve the privilege of adopting all such legitimate changes as may be fairly embodied within the spirit and scope of the invention as claimed.

I claim:

1. Fastening means for bag frames having a pair of frame members connected together for movement toward and away from each

other, said means comprising a retainer piece on one member with an upstanding catch lug forming an open space between it and the member, a slide having opposing rigid plates disposed in flatwise sliding contact with the outer and inner faces of the second member, a shank united with said plates and providing a rigid connection therebetween, means affording a guide for said shank, and a projection on the shank adapted to enter said open space and engage behind said catch lug.

2. Fastening means for bag frames having a pair of frame members connected together for movement toward and away from each other, said means comprising a lateral retainer piece on one member, an engageable strip forming an open pocket-space between it and said member, provided on said retainer piece, a slide, separate opposing bearing parts disposed in flatwise sliding contact with the outer and inner faces of the second member, one of said bearing plates being rigid with the slide, a shank uniting said bearing parts and providing a rigid connection therebetween, there being an elongated slot in the second member between the outer and inner faces thereof and said shank extending transversely through and being slidably fitted in said slot, and a projecting portion on said shank adapted, on movement of the slide in one direction, to enter said pocket-space and engage behind said engageable strip.

3. Fastening means for bag frames embodying first and second frames connected together for closing movement, the former having a laterally projecting top for abutment by the second frame when the frames are closed, said top having therein parallel elongated guide slots, a lateral retainer piece on the first frame, an engageable strip forming an open space between it and the first frame, provided on said retainer piece, a slide flatwise slidable along said top, shanks carried by the slide and slidably fitting said slots, a bearing plate having flatwise sliding fit on the underside of said top, rigidly connecting said shanks, an extension on one shank extending well below said bearing plate, said retainer piece, its open space and strip, all being positioned below said top and concealed thereby when the frames are in abutment, and said extension, on the movement of the slide in one direction, being adapted to enter said space and engage behind said strip.

In testimony that I claim the foregoing as my invention, I have signed my name hereto.

HARRY LEBERMAN.
